UNITED STATES PATENT OFFICE.

CHARLES F. HENRY AND JOHN M. HULETT, OF BELVIDERE, ILLINOIS, ASSIGNEES TO
NATIONAL SEWING MACHINE COMPANY, OF BELVIDERE, ILLINOIS, A CORPORA-
TION OF ILLINOIS.

MECHANICAL MOVEMENT AND BASE THEREFOR.

Application filed April 18, 1921. Serial No. 462,239.

To all whom it may concern:

Be it known that we, CHARLES F. HENRY and JOHN M. HULETT, citizens of the United States, residing at Belvidere, in the county 5 of Boone and State of Illinois, have invented certain new and useful Improvements in Mechanical Movements and Bases Therefor, of which the following is a specification, reference being had to the accompanying drawings and to the reference characters marked thereon, which form a part 10 of this specification.

This invention relates to mechanical movements and metal base therefor.

15 Among the objects of the invention are to produce a simple means for converting the rotary motion of a driving shaft into the reciprocating motion of a pivoted or rocking lever; to produce a gearing support 20 which shall be in one piece and in which all or nearly all of the operating parts may be enclosed in a protecting casing; and to produce a simple and effective mechanism and support therefor, which may be assembled as 25 a unit and then placed as a unit into final position in the machine location where it is to be used.

To these ends, our invention consists in the devices and combination of devices 30 herein illustrated, described and pointed out in the appended claims.

In the drawings:

Fig. 1 is a side elevation, partly broken away, of a structure embodying our invention.

35 Fig. 2 is a plan view of a portion of the top of the structure.

Fig. 3 is a side elevation of the structure, looking from a plane at right angles to that 40 from which Fig. 1 is viewed.

Fig. 4 is a top plan view, enlarged, of the gearing, and the casting on which it is mounted.

The invention is shown as applied to a 45 washing machine structure of the dolly or agitator type, comprising a tub A resting upon a frame or table B, having vertical supports 1 and cross brace bars 2. It has a hinged lid 3 in which is mounted the usual 50 operating shaft 4, carrying within the tub the dolly or agitator D, and having mounted upon its upper end, outside the tub, a spur pinion 5. The shaft 4 is given a rotary movement, alternately in opposite directions

by the reciprocation of a rack bar 6, the 55 teeth of which engage the pinion 5. P is a power shaft rotated from any suitable source of power (not shown), usually an electric motor. This shaft carries a spur pinion 7 which meshes with and drives the 60 spur gear 8 rotatably mounted in a suitable bearing 9 on the casting C.

The link 10 is connected at one end to a crank pin 11 on the gear 8 and at its other end to one arm of the rocking lever 12. The 65 other arm of said lever is connected at 13 to the rack bar 6. The pinion 7 is provided with a hub 14 having a circumferential annular groove 15 adapted for engagement with a pin or projecting part on the pivoted 70 lever 16, the latter being connected by the link 17 to an operating lever L. The gear pinion 7 and hub 14 are splined at 18 and may slide upon the shaft P when the lever L is moved, in order to engage or disengage 75 said pinion with the gear 8. Motion may be imparted also to the power shaft P from the shaft 19 through the transmitting bevel gears 20, 21, where an electric motor is not used, the shaft 19 in such case being driven 80 from a gasoline or other engine (not shown) by belt and pulley.

Intermediate the bevel gear 20 and the pinion 7, the power shaft P is provided with a spur pinion 22, which meshes with a 85 larger spur gear 23 mounted on a stud shaft 24, secured to a support 25, which projects upwardly from the casting C. Upon the end of the stud shaft 24 is a spur pinion 26 which is enmesh with a larger spur gear 27. The shaft 28 is mounted in suitable journal 90 bearings 29 in the casting C and carries the gear 27. A vertically disposed shaft 30 is rotatably secured to the frame in a suitable bearing 31 and the shafts 28 and 30 are 95 operatively connected by the bevel gears 32, 33, mounted upon said shafts 28 and 30 respectively. From this shaft 30, any suitable machine, such as a wringer mechanism, may be operated.

Thus, power being applied to rotate the shaft P, the wringer-driving shaft 30 will be operated through the gearing 22, 23, 26, 27, 32 and 33, and the driven machine, such as a wringer for example, will in turn be thrown into and out of motion by its own starting and stopping mechanism, of which there are many standard and conventional 105

types now on the market. Should the lever L have been shifted to throw the pinion 7 into mesh with the gear 8, motion will be also transmitted to the reciprocating rack 6 by the pinion 7, gear 8, crank 11, link 10 and rock bar 12. Should it be desired to operate the wringer mechanism and not at the same time operate the agitator or dolly D, the pinion 7 is thrown out of mesh with the gear 8.

In the grouping of gearing above described, it has been found necessary to make the casting C of the special form illustrated, desirable features of which we will now 15 describe.

The main part of the casting C is substantially a rectangular L-shaped frame, the side 34 being provided with the bearings 25, 29 and 35 for the shafts 24, 28 and P respectively. The side 36 has a journal bearing 37 for the shaft 19, while its opposite, parallel side 38 is extended outwardly at 39 to form a clearance recess for the gear 27. The side 40 is extended circularly at 41 to form clearance for the bevels 31 and 32 and this curved portion 41 is strengthened by a downwardly and hemispherical web member 42. The fulcrum 43 of the lever 16 is mounted on a projecting arm 44. The bearing 9 is formed on the end of the arm 45. A brace 46 extends from the side 36 to the end of the arm 45. Strengthening ribs 47 are formed on the arms 44, 45 and 46.

The casting is bolted to cross bars 48 of the frame by bolts 49. The top margins of the walls 34, 36, 38, 40 and 41 are offset to form a conventional shoulder at 39, to receive the gear cover or top 51, shown in section in Figs. 1 and 3, which latter is bolted 30 down to the casting C by the bolt 52. The interior of the casting C affords a convenient receptacle for a lubricant for the gears, and the cover 51 protects the gears and the 40 lubricant from the accumulation of dust and dirt, and also prolongs the life of the lubricant.

It will be manifest that the casting C presents the greatest strength where strength is required and at the same time contains the 50 minimum amount of metal; and its shape is such that it may be cast in a single piece or unit.

It will also be manifest that the various parts may be assembled upon the casting C in the shop and the whole, as a unit, may then be set in juxtaposition upon the cross-bars of the frame and bolted securely thereto. This results in a great saving of time and considerably reduces manufacturing 60 cost. After being secured in place by the bolts 49, the parts 16 and 17 connected, and the end of the link 10 secured to the crank pin 11, the washing machine may be operated. The shaft 30 will, usually, be cut between its ends so as to form a conventional 65

"slip-joint" union, which will facilitate the installation of the device upon the washing machine frame.

It will be manifest that the shaft 24 may be a stud shaft secured by nuts, as shown, to the casting and bearing 25, the gears 23 and 26 turning loosely thereon, or that the bearing 25 may be the usual journal bearing and the shaft 24 rotate thereon, in which case the gears 23 and 26 will be keyed to the shaft 24 in a familiar manner to rotate therewith.

We claim as our invention:

1. As a new article of manufacture, the casting for a gearing support, comprising 80 a bottom plate of generally rectangular form surrounded by side and end walls, a cover adapted to fit the top margins of said walls, means for removably securing the cover to the casting, one of the walls having a plurality of shaft bearings, a recess in the opposite wall, an arm projecting from one side provided with a lever support at its end, a second projecting arm provided with a shaft bearing, a brace arm, and means for securing said arms and the bottom plate to a fixed support.

2. In mechanism of the class described, a cast metal housing provided with a shaft bearing, a power shaft mounted in said bearing and extending transversely of the housing, a pinion splined to said shaft, an integral bracket extending outwardly from the housing, a lever pivotally mounted on said bracket and operatively connected with the splined pinion, a second bracket extending outwardly from the housing and provided with a bearing, a shaft rotatably mounted in said last mentioned bearing, a spur gear on said shaft adapted to be engaged by said splined pinion, a rocking lever and operative connections between said spur gear and the lever.

3. In mechanism of the class described, a cast metal housing provided with a shaft bearing through one wall, a power shaft mounted in said bearing and extending transversely of the housing, a pinion splined on said shaft outside of the housing, a second pinion on said shaft within the housing, a bracket integral with the housing having a shaft bearing, a shaft in said bearing, a rocking lever, operative connections, including said last mentioned shaft, between said splined pinion and the rocking lever to actuate the latter, means mounted on a bracket integral with the housing for controlling the splined pinion, a second bearing in the housing wall, a shaft rotatably mounted in said last mentioned bearing extending within the housing parallel with and driven from the power shaft, operative connections within the housing between the last mentioned rotatable shaft and a suitable machine mechanism for the purpose of oper- 130

ating the latter, said connections including a train of gears.

4. In mechanism of the class described, a cast metal housing provided with a shaft bearing in one of its walls, a power shaft mounted in said bearing and extending beyond each end thereof, a pinion splined to said shaft outside of the housing, a second pinion on said shaft within the housing, a bracket integral with the housing, a shaft bearing on the bracket, a gear carrying shaft in said bearing, a rocking lever, operative connections including said gear carrying shaft, between the splined pinion and the rocking lever to actuate the latter, means for controlling the splined pinion, a second bearing on the housing wall, an aligned bearing within the housing, a shaft rotatably mounted in said last mentioned bearings and extending parallel with and driven from the power shaft, operative connections between the pinion on the power shaft and a suitable machine mechanism to operate the latter, said connections including a train of gears and a 25 pair of beveled gears, one of the beveled gears being mounted on said rotatable shaft.

5. A mechanical movement of the character described, comprising a metal casting, a driving shaft rotatably mounted thereon, a rocking lever, operative connections between the lever and said shaft for actuating the lever, means for controlling said connections, a stub shaft rotatably mounted in said casting and adapted for connection with and to operate a suitable machine mechanism, a rotatable shaft operatively connected with said stub shaft, a stud shaft intermediate said rotatable shaft and the driving shaft, gearing connecting the last mentioned shaft with the rotatable shaft and the driving shaft, said metal casting including a removable cover whereby most of the gearing is enclosed. 30 35 40

In testimony that we claim the foregoing as our invention we affix our signatures, in the presence of two witnesses, this 4th day of April, 1921.
